FIG. 1

FIG. 2

FIG. 3

INVENTOR
LEONARD J. MAYER

BY

Wm. H. Dean
AGENT

UNITED STATES PATENT OFFICE

2,680,906

ENVELOPE OPENER

Leonard J. Mayer, La Mesa, Calif.

Application October 31, 1949, Serial No. 124,685

2 Claims. (Cl. 30—293)

1

My invention relates to an envelope opener, more particularly for cutting open one end of a conventional letter envelope or the like, and the objects of my invention are:

First, to provide an envelope opener of this class which employs conventional razor blade means for slitting envelopes, whereby they may be easily and precisely cut along one side or end, through one thickness of said edge, so that the removal of the contents thereof may be readily facilitated;

Second, to provide an envelope opener of this class which is very precise and performs in a manner which provides a very neat cut in envelopes, so that said envelopes may be preserved, if desired, without being unduly mutilated;

Third, to provide an envelope opener of this class having a sharp blade and an adjustable guide screw axially adjustable relative to said blade, having a head which maintains certain guiding control of envelopes passing through the opener, whereby they are forced to traverse the edge of said blade;

Fourth, to provide an envelope opener of this class having an envelope receiving slot therein, wherein a blade is fixed in interfering relation with said slot, so that precise control of the cutting of an envelope may be maintained, which may be accomplished very close to the edge of the envelope, so that the contents of the envelope are not damaged in the process of cutting the envelope open with said opener;

Fifth, to provide an envelope opener of this class which may be used to open envelopes with a minimum amount of effort and attention on the part of the operator;

Sixth, to provide an envelope opener of this class which attains exceptionally uniform results in the cutting of the ends of envelopes near one edge, as desired;

Seventh, to provide an envelope opener of this class which is very compact in proportion to its function; and

Eighth, to provide an envelope opener of this class which is very simple and economical of construction, efficient in operation, and which will not readily deteriorate or get out of order.

With these and other objects in view, as will appear hereinafter, my invention consists of certain novel features of construction, combination and arrangement of parts and portions, as will be hereinafter set forth in detail and particularly described in the appended claims, reference being had to the accompanying drawings 55

2

and to the characters of reference thereon, forming a part of this application, in which:

Fig. 1 is a top or plan view of my letter opener; Fig. 2 is an enlarged sectional view, taken from the line 2—2 of Fig. 1; and Fig. 3 is an enlarged fragmentary sectional view, taken from the line 3—3 of Fig. 1.

Similar characters of reference refer to similar parts and portions throughout the several views of the drawings.

The frame 1, blade 2, blade retainer 3, guide screw 4, and the pad 5, constitute the principal parts and portions of my envelope opener.

The frame 1 of my envelope opener is substantially rectangular, as shown in Fig. 1 of the drawings, and is provided with a slotted portion 1a therein, communicating with a blade-holding recess 1b, in which the blade 2 is positioned, and held by a protruding rib 1c, which engages the normally slotted portion 2a of a conventional razor blade 2, which is provided with a sharp edge portion 2b, arranged in acute angular relationship to the slot 1a, all as shown best in Figs. 1 and 3 of the drawings.

The frame 1 is provided with dovetailed ways portions 1d with which the blade retainer 3 is slidably engaged. Beneath the blade retainer 3 is a pad 5, which engages the outer surface of the blade 2, and which is held by the blade retainer 3. The guide screw 4, as shown in Fig. 3 of the drawings, is provided with a head portion 4a and a screw-threaded shank portion 4b, which is internally screw-threaded within the frame 1, beyond the slot 1a, with which the head portion 4a, at its inner side 4c, may be substantially flush, as shown in Fig. 3 of the drawings.

The operation of my envelope opener is substantially as follows:

The edge of an envelope may be inserted 40 in the slot 1a and engaged with the bottom portion 1e therein, substantially beyond the sharp edge 2b of the blade 2, which regulates the distance the blade 2 cuts from the edge of the envelope. When the envelope has been placed in the slot 1a, against the lower portion 1e thereof, it is moved longitudinally of its edge, adjacent the bottom 1e of the slot 1a, past the edge of the blade 2, adjacent the head 4a of the guide screw 4, at its inner flat surface 4c. Thus, the end or side edge of the envelope may be neatly cut through one thickness, as desired. Adjustment of the guide screw 4 longitudinally of its axis may be made to regulate the spaced relationship of the surface 4c of the head 4a of the screw 4 relative to the cutting edge portion 2b of the

blade 2, to leave one thickness of paper uncut. It is important to note that adjustment of said screw allows surface 4c to be retracted from said cutting edge 2b and away from coplanar relation with the adjacent envelope-guiding wall portion 5 of the slot 1a, and this feature facilitates the severance of only a single thickness of the envelope.

It will be noted that the angular relationship of the cutting edge 2b of the blade 2 provides for gradual shearing action on the paper of an envelope when forced past the blade 2 intermediate the head portion 4a of the guide screw 4 and said blade 2. It will be noted that the frame 1 maintains the blade 2 in spaced relationship from the bottom of the recess 1b by means of the protrusions 1f, which provide cutting clearance for the blade 1 relative to the bottom 1b of the blade supporting recess in the frame 1.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In an envelope opener, a frame having a recessed area in one face thereof, said frame having a slot adjacent one end extending normal to said recess, a part of said slot opening into one corner of said recessed area, a bore in said frame having its axis normal to said slot, said bore having a relatively small threaded section on one side of said slot and a relatively larger screw head-accommodating enlargement in said frame on the other side of said slot, said enlargement opening into said recessed area, a blade in said recessed area having a cutting edge, one corner of said cutting edge extending into said slot, means for retaining said blade in fixed position, a guide screw having a shank screwed into

4
said threaded section, a head on said screw having a flat inner surface in opposing and cooperative relationship with said one corner of said cutting edge for frictionally engaging and supporting articles being cut, whereby said flat surface may be accurately adjusted relative to said cutting edge to cut through one thickness of paper.

2. In an envelope opener, a frame having a recessed area in one face thereof, said frame having a slot adjacent one end extending normal to said recess, a part of said slot opening into one corner of said recessed area, a bore in said frame having its axis normal to said slot, said bore having a relatively small threaded section on one side of said slot and a relatively larger screw head-accommodating enlargement in said frame on the other side of said slot, said enlargement opening into said recessed area, a blade in said recessed area having a cutting edge, one corner of said cutting edge extending into said slot, a blade retainer approximately equal in size to said recessed area and removably and resiliently positioned in said recessed area to maintain said cutting blade in fixed position, a guide screw having a shank screwed into said threaded section, a head on said screw having a flat inner surface in opposing and cooperative relationship with said one corner of said cutting edge for frictionally engaging and supporting articles being cut, whereby said flat surface may be accurately adjusted relative to said cutting edge to cut through one thickness of paper.
